United States Patent Office

Des. 212,035

Patented Aug. 20, 1968

212,035

PITCHER

Frank J. Benes, Lancaster, Ohio, assignor to Anchor
Hocking Glass Corporation, Lancaster, Ohio, a corporation of Delaware

Filed Apr. 20, 1967, Ser. No. 6,764

Term of patent 14 years

(Cl. D44—21)

FIG. 1 is a side elevational view of a pitcher showing my new design as applied to a pitcher or similar article; FIG. 2 is a top view thereof; and

FIG. 3 is a rear view thereof.

I claim:

The ornamental design for a pitcher, substantially as shown.
